OPERATOR FOR ELECTRIC SWITCHES

John C. Ponstingl, Pittsburgh, Pa., assignor to
Westinghouse Electric Corporation, East Pittsburgh, Pa., a corporation of Pennsylvania

Application January 30, 1948, Serial No. 5,358

8 Claims. (CL 175—336)

1

My invention relates to electromagnetically operable switches and, more particularly, to certain features of the operator elements of such switches.

One broad object of my invention is the provision of an improved operator for an electromagnetically operable switch.

Another object of my invention is the provision of an operator assembly that may be assembled and disassembled as a unit from the electromagnetic switch, and which in use provides for substantially rectilinear movement of the operator upon magnetization of the armature for actuating the operator.

Other objects and advantages will become readily apparent from a study of the specification and the accompanying drawing illustrating certain preferred embodiments, and in which:

Figure 1 is a perspective view of the operating means for a switch;

Fig. 2 is a side view of my invention with certain parts shown in section to more clearly illustrate the novel features;

Fig. 3 is a plan view of a detail of my invention; and

Fig. 4 is a plan view of a modification of a detail of my invention.

In the figures of the drawing, the reference character 1 designates the base or control panel to which my device, in use, is secured. The E-shaped magnet 2 is provided with a pair of heavy laminations 3 at the outer surfaces provided with the flanges 4 and 5 for mounting the E-shaped magnet to the base 1.

The magnet structure is so mounted on the base 1 that the open part of the E faces downwardly, that is, the legs 6, 7 and 8 are directed down, and with the stem 9 being disposed so as to project horizontally from the base. The disposition mentioned of the parts is the usual one in use but my invention is not limited in use to the particular position shown or described. The disclosure of my device with reference to a vertical base 1 is merely illustrative.

The middle leg 7, or core, carries the energizing coil 10 held in place by friction or some simple readily displaceable coil holding means not constituting part of my present invention.

To the forward leg 8, I secure the generally rectangular plate 11. This plate 11 is provided with tabs, or tongues, 12 and 13 that project beyond the upper surface of the stem 9 and the lower surface of the armature 14. These tabs are slightly undercut at the junction of the tab with the main portion of the rectangular plate. The

2

amount of undercut is such that the transverse dimension of the tab at the undercut is substantially equal or a trifle less than the distance between points 15 and 16 on the frame 17 shown in Figs. 1 and 3, or substantially equal or a trifle less than the distance between edges 18 and 19 of frame 20, shown in Fig. 4.

The frames 17 and 20 have a picture frame appearance and are selected to quite thin tough sheet metal to thus in effect act as a knife edge bearing element on the tab necks when the parts are assembled as shown in Figs. 1 and 2.

The armature carrying operator frame is built up of two parts identical in shape. In the manufacture of the parts, a single stamping die is used. The right-hand part 21 is a generally U-shaped flat member having outwardly directed feet 22 and 23 connected to the ends of the legs of the U. The upper foot 22 has a toe member 24 bent at right angles toward the left, as seen in Fig. 1, of the foot 22. The toe member 24 is provided with a rearwardly directed projection 25 to which the switch elements to be operated are secured.

The lower foot 23 is provided with a toe member 26 bent at right angles toward the left, as seen in Fig. 1, of the foot 23. The toe 26 is provided with a projection, or abutment, 27 bent upwardly and at right angles to the foot 26. The abutment 27, when the parts are in the position shown in Figs. 1 and 2, faces in a plane parallel to the plate 11. The abutment 27 is provided in its forward face at its mid-region with a cylindrical button 28.

The left-hand part 31 of the armature carrying operator frame is identical in shape to the part 21 but in assembled position with reference to part 21, the part 31 is turned through a half circle on a horizontal axis. The left-hand part has the parts 32, 33, 34, 35, 36, 37 and 38 which correspond, respectively, to elements 22 to 28 as to structure and substantially as to function.

The holes 12 and 13 are the surfaces facing the buttons 28 and 38 provided with similar buttons 30 and 40.

The upper frame 17 is hooked over the tab 12 and abutment 37 whereas the lower frame 17' is hooked over the abutment 27 and the tab 13. A compression spring 41 is disposed between the tab 12 and abutment 37 and is so positioned that the spring ends engage the buttons 30 and 38. A similar compression spring 42 is disposed between the tab 13 and abutment 27 and the spring ends engage the buttons 28 and 40. The springs 41 and 42 thus subject the frames 17 and 17' to tension and the armature carrying operator is

thus held on plate 11. The elements 11, 17, 17', 21, 31, 41 and 42 thus form a unitary assembly that may be mounted on the E-shaped magnet as a unit by the two small screws 43 and 44.

The armature 14 is secured to the armature operating member by a suitable shaft 45 rotatably disposed in the bearings 46. From the foregoing description, it is apparent that the armature actuated parts move substantially rectilinearly, since the construction is functionally 10 in the nature of a parallelogram having pivotally mounted side members and end members.

Further, since the frames 17 and 17' are of relatively thin material, the bearings for these frame members are substantially knife edge. 15 Friction loss is thus a minimum.

The frames for the end elements of the parallelogram structure need not be as shown in Figs. 1, 2 and 3. In fact the preferred embodiment is as shown in Fig. 4. For either type of frame the opening in the frame is such as to readily receive the end tabs on the plate 11 but the end shape, as seen in Figs. 3 and 4, is such that as the frame slips to its end, or operating, position, the frame is locked in position and cannot be removed without compressing the compression springs.

While I have shown but one embodiment, except for the frames 17 and 20, my invention is not limited to the single showing made but is to be limited only by the scope of the claims 30 hereto appended.

I claim as my invention:

1. An operating means for an electromagnetic switch, comprising, a stationary magnet structure provided with means at one end for supporting the structure on a suitable base, an energizing coil for the magnet structure, a plate mounted at the other end, said plate being longer than the width of said structure and so mounted on the structure that the ends thereof at each end project beyond the magnet structure, an operating member including abutments disposed transverse of the width of the magnet structure and including guide means disposed in juxtaposition to the other end of said magnet structure to thus guide the operating member for substantially rectilinear movement, an armature mounted on the lower portion of the operating member, a frame of relatively thin flat material disposed to have its end hooked over the upper abutment of the operating member and the upper projecting end of the plate, a similar frame at the lower end of the operating member similarly disposed between the plate and lower abutment of the operating members, and two compression springs disposed respectively between the upper projection of the plate and the upper abutment and the lower projection of the plate and the lower abutment.

2. Operating means for an electromagnetically operable contractor comprising, in combination, an E-shaped magnet structure having a stem and three legs, means on one outer leg of the structure for mounting the structure on a suitable base, an energizing coil on the middle leg, a plate secured to the edge of the other outer leg, said plate projecting beyond the edge of the stem and the ends of the legs, a cage having a pair of cross-bars, one normally disposed in spaced facing relation to one end of the plate, and the other similarly disposed with relation to the other end of the plate, an armature secured on the cage adjacent the cross-bar disposed in facing relation to the end of the middle leg, said cage having side members disposed in closely spaced

relation to the leg carrying the plate to thus guide the cage for movement parallel to the faces of the E-shaped magnet structure, a rectangular frame of relatively thin material hooked over one end of the plate and on the cross-bar disposed in facing relation to the one end of the plate, a second similar frame similarly mounted at the other end of the plate and corresponding cross-bar, two compression springs one disposed to coat with one plate end and corresponding cross-bar and the other disposed to coat with the other plate end and the cross-bar facing this other plate end, said cage, plate, and springs forming a unitary assembly that may be mounted and removed from the magnet structure as a unit to facilitate replacement of the energizing coil.

3. Operating means for an electromagnetically operable contactor comprising, in combination, an E-shaped magnet structure having a stem and three legs, means on one outer leg of the structure for mounting the structure on a suitable base, an energizing coil on the middle leg, a plate secured to the edge of the other outer leg, said plate projecting beyond the edge of the stem and the ends of the legs, a cage having a pair of cross-bars, one normally disposed in spaced facing relation to one end of the plate and the other similarly disposed with relation to the other end of the plate, a flat projection on each cross-bar disposed in a plane substantially parallel to the plate, an armature secured on the cage adjacent the cross-bar disposed in facing relation to the end of the middle leg, said cage having side members disposed in closely spaced relation to the leg carrying the plate to thus guide the cage for movement parallel to the faces of the E-shaped magnet structure, a rectangular frame of relatively thin material hooked over one end of the plate and on the projection on the cross-bar disposed in facing relation to the one end of the plate, a second similar frame similarly mounted at the other end of the plate and corresponding cross-bar, two compression springs one disposed to coat with one plate end and corresponding cross-bar and the other disposed to coat with the other plate end and the cross-bar facing this other plate end, said cage, plate, and springs forming a unitary assembly that may be mounted and removed from the magnet structure as a unit to facilitate replacement of the energizing coil.

4. Operating means for an electromagnetically operable contactor comprising, in combination, an E-shaped magnet structure having a stem and three legs, means on one outer leg of the structure for mounting the structure on a suitable base, an energizing coil on the middle leg, a plate secured to the edge of the other outer leg, said plate projecting beyond the edge of the stem and the ends of the legs, a cage having a pair of cross-bars, one normally disposed in spaced facing relation to one end of the plate and the other similarly disposed with relation to the other end of the plate, a flat projection on each cross-bar disposed in a plane substantially parallel to the plate, said plate being provided with a V-shaped notch at each end, the open ends thereof being directed away from the cross-bars, said projections each being provided with a V-shaped notch, the open ends thereof being directed away from the plate, an armature secured on the cage adjacent the cross-bar disposed in facing relation to the end of the middle leg, said cage having side members disposed in closely spaced relation to the leg carrying the

plate to thus guide the cage for movement parallel to the faces of the E-shaped magnet structure, a rectangular frame of relatively thin material hooked over one end of the plate into the V-shaped notch and on the V-shaped notch in projection on the cross-bar disposed in facing relation to the one end of the plate, a second similar frame similarly mounted at the other end of the plate and corresponding cross-bar, two compression springs one disposed to coact with one plate end and corresponding cross-bar and the other disposed to coact with the other plate end and the cross-bar facing this other plate end, said cage, plate and springs forming a unitary assembly that may be mounted and removed from the magnet structure as a unit to facilitate replacement of the energizing coil.

5. Operating means for an electromagnetically operable contactor comprising, in combination, a plate in a general sense rectangular in shape, a cage member having end portions disposed in parallel relation to the ends of the plate, a pair of rectangular frames each of relatively thin material and generally the contour of a picture frame, one of said frames being hooked at one end over one end of the plate and the other end over the facing end portion on the cage member and the other of said frames being similarly mounted at the other end of the plate and the corresponding facing end portion of the cage, a compression spring disposed between the other end of the plate and the facing end portion on the cage member to thus subject the second frame to tension, a magnet structure fitting into the cage, said plate being secured to the magnet structure whereby the cage is free to move substantially rectilinearly, an armature secured to the cage member in the region of one of the end portions, and an energizing magnet structure for acting on the armature.

6. Operating means for an electromagnetically operable contactor, comprising, in combination, a flat member having two tabs projecting from the edge thereof at substantially diametrical regions of the member, a cage member in the form of an open frame having two tabs projecting from the second member at substantially diametrical regions of the second member, a rectangular open frame of relatively thin material hooked over one pair of tabs on the flat member and cage member and a similar rectangular open frame of relatively thin material hooked over the other pair of tabs on the flat member and cage member to thus form a parallelogram type assembly, two compression springs one disposed substantially in the plane of one rectangular member and the other disposed substantially in the plane of the other rectangular member, said springs engaging the flat member and cage member to thus subject the rectangular frames to tension, a magnet structure fitting into the cage member to abut against the flat member, means for

securing the flat member to the magnet structure, whereby the cage member is disposed for movement substantially rectilinearly with reference to the magnet structure, an armature mounted on the cage member, and an energizing coil on the magnet structure for actuating the armature.

7. Operating means for an electromagnetically operable contactor comprising, in combination, a parallelogram construction including a pair of side members, a pair of open frame end members of thin material hooked over corresponding ends of the side members, two compression springs disposed respectively between corresponding ends of the side members substantially within the frames of the end members to thus hold the parts together as a unit, a magnet structure, one of said side members being in the form of an open frame to receive the magnet structure between the edges of the frame, means securing the other side member to one end of the magnet structure, means at the other end of the magnet structure for securing the magnet structure to a suitable base, or control panel, an armature secured at the region of one of the freely movable corners of the parallelogram construction, and an energizing coil disposed on the magnet structure for actuating said armature.

8. Operating means for an electromagnetically operable device comprising, in combination, a magnetic base, a parallelogram construction including a pair of side members provided with tabs at their ends, which tabs are disposed in parallel relation with the side members, a pair of end members of relatively thin material and in the general shape of a picture frame having their ends hooked over corresponding tabs of the side members, whereby the end members by reason of the thinness of the material form knife-edge bearings on the tabs, a single compression spring disposed between the tabs at one end, a similar single compression spring similarly disposed at the other end, whereby said springs hold the parallelogram construction together as a unit, one side member being secured to the base, an armature secured to the other side member, and means for actuating the armature.
